Application July 15, 1941, Serial No. 402,498

15 Claims. (Cl. 250—36)

This invention relates to a blocking tube oscillator that is particularly useful in television circuits although it is not restricted to this particular use. While blocking tube oscillators have been known for a long time, by the present invention improvements are made in the blocking tube which result in more stable performance and in ability to reject interfering signals more completely. Blocking tube oscillators are used, for example, in television receivers to generate control pulses for producing sawtooth wave forms for scanning. In some cases the blocking tube oscillator delivers only an impulse at scanning frequency and in other cases the blocking tube oscillator circuit also includes components to cause the actual sawtooth wave form to be generated directly.

Blocking tube oscillators are generally synchronized or controlled in their trigger off periods by means of incoming synchronizing signals. It is very desirable that a blocking tube oscillator be selectively responsive to the synchronizing pulses while at the same time it rejects other types of signals which are present in the incoming waves.

Earlier forms of blocking tube oscillators utilized an iron-cored transformer for feeding energy back from the plate circuit to the grid circuit of the blocking tube. The performance of such circuits depends upon over coupling so that the tube tends to oscillate at a frequency determined by the constant of the iron-cored transformer and the grid circuit is provided with the condenser and resistance network so that the tube builds up a bias voltage at the initial oscillation sufficient to cut the tube off for an interval. This condenser and resistance network slowly discharges to the point where the tube again tends to oscillate until another blocking cycle occurs. In the prior devices the frequency at which the circuit would tend to oscillate was determined by the iron-cored transformer and bore no particular relation to the synchronizing signal. In those circuits the synchronizing signal generally took the form of a square wave impulse of short duration which might be coupled to the blocking tube transformer by use of a third winding for example. However, such a circuit was susceptible to extraneous noise signals which simulated the synchronizing pulses.

These and other difficulties are overcome by the present invention. In carrying out this invention the iron-cored transformer is replaced by a radio frequency transformer at least one winding of which is tuned to the frequency of a car-

rier, pulses of which are used for synchronizing purposes. In this way only those synchronizing signals which have the frequency of this carrier are passed by the transformer and furthermore this same frequency of resonance in the transformer is used as the oscillation frequency for the blocking action.

This invention will be specifically described as being suitable for using carrier synchronizing pulses for vertical scanning frequency similar to those described in my Patents Nos. 2,249,942 and 2,249,943. However, the invention is also suitable for other carrier synchronizing pulses such as the horizontal channel, for example, where the carrier frequency may be of the order of 3 megacycles, more or less.

My Patent 2,249,943 shows one way of utilizing a carrier signal at a receiver employing a thyratron type of discharge tube. There are other ways of using a carrier synchronizing pulse with a blocking tube oscillator but the particular way utilized in the present invention combines the blocking tube action with the synchronizing selective action in one simple radio frequency transformer.

The invention may be understood from the description in connection with the accompanying drawings in which:

Fig. 1 is a schematic drawing showing a blocking tube oscillator using a radio frequency feed back transformer;

Fig. 2 represents the wave form of a few bursts of carrier for synchronizing;

Fig. 3 represents the wave form of the voltage on the grid of the blocking tube oscillator;

Fig. 4 represents the corresponding wave form of the plate current in the blocking oscillator tube;

Fig. 5 represents the output sawtooth wave form; and

Fig. 6 is a view similar to Fig. 1, showing a modification.

In the drawings, reference character 1 indicates a lead which introduces the synchronizing signals for a television receiver and may also include picture components which are to be removed subsequently in the known ways by amplitude selection. Condenser 2 connects these signals to the grid 3 of the tube 4. Resistor 5 maintains the bias on grid 3. The plate 6 carries only the synchronizing signals since tube 4 performs a synchronizing separator function. These synchronizing signals are fed to the winding 7 of the transformer 8 which has two un-tuned windings 7 and 9 and a winding 10 which

may be tuned by condenser 11 so that it resonates at the frequency of the incoming synchronizing pulse of carrier. These carrier pulses are applied through the secondary 10 of transformer 8 to the grid 12 of tube 13 which is the blocking oscillator tube. The plate 14 of this tube is connected to winding 9 of the transformer 8 with such polarity as to feed energy back into the grid circuit by means of winding 10. In this way the tube 13 in conjunction with the transformer 8 forms an oscillator. Insertion of resistor 15 shunted by condenser 16 in the grid return lead 17 of winding 10 provides a means whereby oscillations which take place in tube 13 are caused to charge up condenser 16 to a point which will bias the grid 12 to cut off with respect to the cathode 18. The tube 13 then becomes inactive for an interval until the charge on condenser 16 has leaked off through the variable resistor 15 sufficiently to allow the oscillations to resume in tube 13, starting a new blocking cycle. This pulsating flow of current in the plate circuit of tube 13 is used as a discharge mechanism across the condenser 20 which is connected by lead 21 to one end of winding 9 the other end of which is connected by lead 22 to the plate 14.

The fixed resistor 23 and adjustable resistor 24 in series serve to charge condenser 20 from the B+ supply during the blocked interval of tube 13. In this way conductor 25 is caused to carry a sawtooth wave form which may be applied to deflection plates of a cathode-ray tube in the conventional way for sweep purposes, either for television scanning or oscilloscopes or the like.

Fig. 2 shows somewhat diagrammatically a wave form representing bursts of carrier energy lasting for short intervals with longer intervals between bursts free of signal, which may be applied through the lead 1. The carrier waves are of high frequency but the repetition of the bursts 30 are of much lower frequency. For example, these bursts may be either at the scanning rate for television lines or television fields. A 500 kilocycle carrier wave at a pulse repetition rate of 60 per second for vertical scanning is described in my Patent 2,249,942. Also a carrier of 3 megacycles with pulse repetition rate of approximately 15,000 per second, for example, might be used for horizontal synchronization. In Fig. 2 reference character 30 represents a few oscillations of each burst of the synchronizing carrier and 31 represents the dormant interval in which no signals of this frequency are present.

The wave form 34 in Fig. 3 represents the voltage at the grid 12 of tube 13. The dotted line 35 represents the critical voltage level at which tube 13 begins to conduct current. The tube 13 has a spontaneous blocking action in which the dotted wave form 36 would be followed except for the synchronizing information or impulses 30. At the point 37 the voltage of grid 12 would cause a condition so that plate current would begin to flow. The windings 9 and 10 are so connected that this increase of plate current would induce a further positive voltage on grid 12, causing grid current to flow since grid 12 becomes positive with respect to cathode 18. However, the presence of the synchronizing pulse 30 causes the grid 12 to reach the critical triggering voltage at the point 38 in the wave form instead of the point 37, thus drawing the spontaneous period of the blocking oscillator in step with the synchronous period of the incoming synchronizing

bursts 30 of carrier. When the grid 12 is made to swing positive as described above, current flows between the grid 12 and cathode 18 so that the condenser 16 is charged up so as to bias the grid 12 more negatively. As soon as grid 12 goes negative enough to begin to cause a decrease in the plate current through winding 9, this decreasing current induces through winding 10 a further negative bias on grid 12 which causes the oscillation to cease and leaves a charge on condenser 16 so that grid 12 is held considerably beyond cut-off for an interval. The resistive leak 15, however, gradually removes the charge on condenser 16 until the grid 12 again starts a new blocking cycle. In the regions from about 39 through 40 to about 41 the blocking oscillator is relatively unresponsive to incoming signals of either synchronizing pulses or extraneous noise. In the region from about 41 to 42 along the wave form the oscillator is readily susceptible to lock-in by incoming synchronizing pulses and is also susceptible to noise. However, by the use of the tuned transformer 8 the circuit is highly selective to accept the desired synchronizing carrier and to reject extraneous noise even in this interval. In the region from 42 to 43 the tube 13 is conducting and therefore the winding 10, heretofore highly resonant, is now heavily damped by the conducting grid 12 so that once the blocking tube action is triggered off at 38 by a burst 30 of incoming synchronizing carrier the synchronizing channel is effectively disconnected for further impulses either of synchronizing or noise nature until the next sensitive period of the blocking action is reached. The region 42 to 43 is shown on the wave form 44 as an envelope or low frequency component of the probable waves on grid 12. The voltage on grid 12 probably takes the form of an oscillatory wave in the region 42 to 43 having the natural period of the tuned circuit determined by transformer winding 10 and the tuning condenser 11 modified by the parallel circuit components. In prior devices this natural period of oscillator which may introduce a fine structure wave form in the region from 42 to 43 was determined by an iron-cored transformer and had no particular relation to the incoming synchronizing pulse carrier frequency.

The wave form 44' in Fig. 4 shows the current with peaks 45 along the lead 21 and Fig. 5 shows the sawtooth wave form of voltage 46 resulting from the capacity 20 and resistances 23 and 24 which wave form passes along the lead 25 to the deflecting plates.

Fig. 6 shows another embodiment of the invention which in principle is similar to the circuit shown in Fig. 1. The actual values of the different circuit components which were used in one embodiment of the invention are given. Tests have shown the superiority of this type of blocking tube oscillator with radio frequency synchronizing signals over the prior blocking tube oscillators using the square wave type of synchronizing signals.

In Fig. 6 the blocking oscillator transformer 51 has two windings 52 and 53 connected in series, the winding 52 being left untuned while the winding 53 is shown as being tuned to 530 kilocycles by means of the condenser 54. The double triode tube 55 which in this embodiment is a 6C8G type has its first section connected as a blocking oscillator in which the grid 57 receives its feed-back energy from the winding 53 through the coupling condenser 58. This condenser 58 receives a

charge during the blocking action so that the grid 57 is driven beyond the cut-off point with respect to cathode 60 until such time as the fixed resistor 61 and the adjustable resistor 62 leak the charge off of the condenser 58 so as to allow the first triode section of tube 55 to conduct current again. The plate 64 of this section provides the blocking oscillator feed-back to the winding 52 of the transformer 51. The coupling between windings 52 and 53 is great enough to cause the blocking oscillator action as explained above in connection with Fig. 1. The power supply voltage for the plate 64 is applied through the winding 52 by means of the conductor 65. The resistor 66 and condenser 67 serve as a de-coupling filter to reduce radiation from this circuit and to prevent spurious pickup in this circuit from other circuits connected to the power supply. A low resistance 70 to ground is inserted into the circuit of the cathode 60. This resistance 70 acts jointly as a load circuit to deliver signal from the first triode section of the tube 55 and also acts as an input resistor for the synchronizing signals which are injected into the blocking oscillator through the cathode. The synchronizing signals, which may, for example, be bursts of 530 kilocycle waves, are first separated from the picture components and horizontal synchronizing components in well known ways by circuits not shown. Means for obtaining the separated 530 kilocycle carrier bursts for vertical synchronizing have been described in my Patent 2,249,943, supra. These synchronizing bursts of carrier frequency are applied to the cathode 60 by means of the small coupling condenser 72, the resistance 73 being part of the output circuit from the previous separating circuits. The conductor 74 leads an output impulse from the cathode 60 to the grid 75 of the next triode section of the tube 55. The signal on the conductor 74 is a short burst of energy somewhat similar to that shown in Fig. 4. This burst of voltage corresponds to the current passed from plate 64 to cathode 60 in the first section of the tube during the conducting portion of the blocking tube oscillator cycle since this signal on conductor 74 contains the residual of the synchronizing signal coupled through condenser 72 and contains also the oscillatory current of the blocking oscillator action. It is desirable to pass the signal through the integrating network consisting of resistor 77 and condenser 78 thus arriving at an envelope voltage on the conductor 79 which is similar to that illustrated in Fig. 4. The resistor 81 is inserted between the conductor 79 and the grid 75 for further filtering and to allow self-bias on the grid 75. In this way the second triode section consisting of grid 75, cathode 82 and plate 84 can generate a sawtooth voltage whose period is controlled by the repetition rate of the blocking oscillator impulses provided from the cathode 60 of the first triode section and filtered as described above. The condenser 85 is connected to the plate 84. It is charged through the resistor 86 during the time when no impulse is applied to grid 75. The condenser 85 is then discharged by current flowing from plate 84 through cathode 82 during the time that the impulse is applied to grid 75. In this way a sawtooth voltage is delivered through the condenser 85 to the conductor 89 which leads to the conventional amplifier equipment for application to a cathode-ray tube.

The circuit of Fig. 6 provides more freedom of amplitude control for the output sawtooth voltage than the somewhat simpler circuit of Fig. 1.

75 When resistor 86 is made variable the amplitude of sawtooth voltage built up across condenser 85 is thereby made controllable without affecting the period of the blocking oscillator cycle in the first triode section nearly so much as the period of the blocking oscillator cycle would be affected in Fig. 1 when the amplitude control 24 is adjusted. However, both Fig. 1 and Fig. 6 show embodiments of this invention which 10 employ a blocking tube oscillator coupling transformer whose resonant frequency is the same as the frequency of the carrier waves in the bursts of synchronizing pulses. While the particular circuit constants given in Fig. 6 are active at 530 15 kilocycles as a carrier frequency for vertical synchronization, it is to be understood that such a circuit using these principles can also be adapted to operate at other carrier frequencies to provide superior synchronization and sawtooth generation for television scanning. For example 20 a 3 megacycle carrier burst at line periodicity of approximately 15,000 bursts per second has proved to be very satisfactory.

25 Some of the advantages of this invention are that there is a more precise or accurate triggering of the oscillator; there is a higher signal to noise ratio than is usual in prior devices; there 30 is a positive control of the oscillator in which the frequency of the control is high and the periodicity is low; the periodicity of the control information is utilized to control the oscillator periodicity; and satisfactory synchronization and stable interlock is secure. The invention is suitable 35 for controlling either horizontal synchronization or vertical synchronization for television systems as well as for controlling other devices.

What is claimed is:

1. In combination, a blocking tube oscillator 40 suitable for generating control pulses for sawtooth waves, and means for applying bursts of carrier frequency energy to said oscillator to trigger the same.

2. In combination, a blocking tube oscillator 45 suitable for generating control pulses for sawtooth waves, and means for applying bursts of carrier frequency energy to said oscillator to trigger the same, said oscillator comprising an air core transformer.

3. In combination, a blocking tube oscillator, 50 suitable for generating control pulses for sawtooth waves, and means for applying bursts of carrier frequency energy to said oscillator to trigger the same, said oscillator comprising a radio frequency transformer.

55 4. In combination, a blocking tube oscillator suitable for generating control pulses for sawtooth waves, and means for applying bursts of carrier frequency energy to said oscillator to trigger the same, and means connected to the output of said oscillator to produce a sawtooth wave of energy.

5. In combination, a blocking tube oscillator, 60 suitable for generating control pulses for sawtooth waves, and means for applying bursts of carrier frequency energy to said oscillator to trigger the same and having its natural period of blocking slightly greater than the period of said bursts of energy.

6. In combination, a blocking tube oscillator, 65 suitable for generating control pulses for sawtooth waves, and means for applying bursts of carrier frequency energy to one of the electrodes of said oscillator to trigger said oscillator.

7. In combination, a blocking tube oscillator 70 suitable for generating control pulses for sawtooth waves, and means for applying bursts of carrier frequency energy to one of the electrodes of said oscillator to trigger said oscillator.

tooth waves, and means for applying bursts of carrier frequency energy to said oscillator to trigger the same and having its coupling network for feed back resonant to the frequency of said energy.

8. In combination, a blocking tube oscillator and means for applying bursts of carrier frequency energy to said oscillator to control its periodicity.

9. A blocking tube oscillator for generating control pulses for sawtooth waves having a coupling network for feed back comprising a winding and means for tuning it so that it is resonant to television synchronizing information of carrier frequency and means for applying to said winding bursts of carrier frequency energy.

10. In combination, a blocking tube oscillator having a coupling network for feed back that is resonant to a desired carrier frequency and means for applying synchronizing pulses of carrier frequency to said network.

11. In combination, a blocking tube oscillator having a coupling network for feed back that is resonant to a desired carrier frequency, and means for applying synchronizing pulses of carrier frequency to said network, said network comprising an air core transformer.

12. In combination, a blocking tube oscillator having a coupling network for feed back that is

resonant to a desired carrier frequency, and means for applying synchronizing pulses of carrier frequency to said network, said network comprising an air core transformer at least one winding of which is tuned to the frequency of a carrier.

13. In combination, a blocking tube oscillator having a coupling network for feed back that is resonant to a desired carrier frequency, and means for applying synchronizing pulses of carrier frequency to said network, said network comprising an air core transformer, the frequency of resonance in said transformer being suitable for use as the oscillation frequency for the blocking action of said tube.

14. In combination, a blocking tube oscillator having a coupling network for feed back that is resonant to television synchronizing information of carrier frequency, and means for applying bursts of carrier frequency energy to said tube.

15. In combination, a blocking tube oscillator having a coupling network for feed back that is resonant to television synchronizing information of carrier frequency, and means for applying bursts of carrier frequency energy to said tube so as to control the oscillator periodicity.

RICHARD L. CAMPBELL.
